E. WEIGELE,
GUIDE RAIL OILER.
APPLICATION FILED OCT. 19, 1918.

Patented Feb. 18, 1919.

UNITED STATES PATENT OFFICE.

EDMUND WEIGELE, OF BERGENFIELD, NEW JERSEY.

GUIDE-RAIL OILER.

1,294,733.

Specification of Letters Patent. Patented Feb. 18, 1919.

Application filed October 19, 1918. Serial No. 258,781.

To all whom it may concern:

Be it known that I, EDMUND WEIGELE, a citizen of the United States of America, residing at Bergenfield, Bergen county, State 5 of New Jersey, have invented certain new and useful Improvements in Guide-Rail Oilers, of which the following is a full, clear, and exact description.

This invention relates to improvements in 10 oiling devices particularly arranged to apply a lubricant to guide-rails for elevators. My improved oiling device is designed to apply, or cause to be applied, a lubricant in small quantities to be spread or applied to 15 the wearing surfaces of the rails by the guide-shoes.

My improved device is adapted to be attached to the upper end or terminal of a 20 guide-rail and is in the form of a reservoir from which the lubricant is fed, or delivered by wicks in combination with flexible conductors or feeders. In other words, the 25 wicks feed the lubricant to the feeders by capillary attraction, the feeders in turn acting as conveyers for the lubricant to trickle down by gravity to and along the guide-rail.

I will now proceed to describe my invention in detail, the novel features of which 30 will be pointed out in the appended claims, reference being had to the accompanying drawings, forming part hereof, wherein:—

Figure 1 is a perspective view of the upper portion of an elevator guide-rail having 35 my improved oiling device applied thereto;

Fig. 2 is a top plan view thereof;

Fig. 3 is a top plan view of the reservoir, the cover being removed, and the rail being 40 broken away;

Fig. 4 is a vertical sectional view, the section being taken on a line 4—4 in Fig. 2; and

Fig. 5 is an enlarged sectional view of one 45 of the wick-tubes, also illustrating the secondary feeder carried thereby.

In the drawing a portion of a guide-rail, for an elevator, is indicated by 6, said guide-rail consisting of a base-member 7 and a 50 guide 8 which is engaged by a shoe on an elevator. For the purpose of applying a lubricant to the wearing surfaces 8^a of the guide 8, I provide an oil-reservoir 9 having a cover 10 hinged thereto at 11. The reservoir 9 carries a web 12 having a recess or 55 jaw 13 to receive the guide 8 of the guide-

rail. In other words, the reservoir is secured to the guide-rail at its upper end, the recess or jaw 13 being formed to receive the upper end of the guide 8. The reservoir 9 60 rests upon the upper end 14 of this guide 8 and is secured thereto by a tap-bolt 15. As can be seen in Fig. 2, the cover 10 is recessed at 16 to clear the head of tap-bolt 15. The recess 13 is virtually a slot in the web 65 12 having an upper wall which rests upon the upper end of the guide 8 and a vertical wall 17 which rests against the face 18 of the guide 8. The bolt 15 passes through the upper wall of the slot 13, as can be seen 70 in Fig. 4.

To convey oil from the reservoir 9 to the surfaces 8^a of the guide 8, I provide (in this instance) three ducts or tubes 19, 20 and 21, each carrying a wick 22 and a flexible resilient feeder 23, better illustrated in Fig. 5. One end of each wick is immersed in the oil, indicated by 24 (Fig. 4), while the other end is located in its duct adjacent the lower end thereof. In other words, each wick projects downwardly in its duct to a point adjacent the point of connection of said duct and a spout 24^a carried thereby, the purpose being to cause the wicks to convey oil, by 80 capillary attraction, to the feeders 23, instead of directly to the rail or guide 8. By this means, I am able to prevent a surplus amount of oil being delivered. Each duct and its spout carries a feeder 23, which consists of a strip of flexible material, such as 85 spring steel, having a hook 25 to engage the upper end 26 of its duct. The oil delivered or fed to the feeders by the wicks will gravitate to the surfaces 8^a of the guide.

Owing to the vibration incident to the 90 elevator mechanism, the oil will gradually travel downwardly along the feeders to the rail. As the feeders 23 are made of relatively thin flexible material, they will vibrate with the elevator mechanism, which 100 includes the guide-rails: hence the feeding of the oil will be greatly facilitated. As can be seen in Fig. 4, the lower end of the feeders will rest in contact with the guide-rail. The feeders being flexible, accuracy of 105 workmanship in applying the reservoir to the rail is not necessary, as said feeders will accommodate themselves to contact with the rail. As will be seen, the spouts 24^a do not contact with the guide 8.

The ducts, and their guides, are preferably removable, said ducts being provided

with threads 27 to engage threads formed in openings in the bottom of the reservoir 9, a lock-nut 28 being employed to hold the ducts in place.

5 What I claim as my invention is:—

1. In a lubricating device, an oil-reservoir, a duct leading therefrom, a flexible resilient feeder within said duct and projecting therefrom, and a wick to convey oil

10 from the reservoir to said feeder.

2. In a lubricating device, a reservoir, a duct carried thereby, and projecting therefrom, a wick carried by the duct and extending into said reservoir adapted to convey oil 15 by capillary attraction from said reservoir to the interior of said duct, a flexible resilient feeder also carried by said duct and projecting from one end thereof, and a hook carried by the feeder to releasably engage

20 the upper end of the duct.

3. A duct, a source of oil supply, a wick carried by the duct extending partly there-

through, the other end of said wick being adapted to be immersed in the oil, and a flexible resilient feeder carried by the duct 25 extending from the point within the duct where said wick stops to a point beyond the end of said duct.

4. In a lubricating device, a reservoir, a duct carried thereby and projecting therefrom, 30 said reservoir being provided with a recess to receive the upper end of an elevator-guide-rail, said recess having an upper wall, to rest upon the upper edge of said rail, a bolt passing through the upper wall 35 of said recess and engaging said guide-rail, and means to convey oil from the reservoir into said duct.

Signed at New York city, N. Y., this 14 day of Oct., 1918.

EDMUND WEIGEL.

Witness:

EDWARD A. JARVIS.
